DANIEL W. DENMAN AND WILLIAM K. TILLOTSON, OF DETROIT, MICHIGAN.

Letters Patent No: 101,236, dated March 29, 1870.

BROILER.

The Schedule referred to in these Letters Patent and making part of the same.

To whom it may concern:

Be it known that we, DANIEL W. DENMAN and WILLIAM K. TILLOTSON, of Detroit, in the county of Wayne and State of Michigan, have invented a new and useful Improvement in Revolving Broilers; and we do declare that the following is a true and accurate description thereof, reference being had to the accompanying drawings, and to the letters of reference marked thereon, and being a part of this specification, in which—

Figure 1 is a vertical section of the device taken through the trunnions;

Figure 2 is a perspective of the case with the cover partially turned; and

Figure 3 is a perspective of the meat-holder open for the reception of the meat to be broiled.

Like letters indicate like parts in each figure.

The nature of this invention relates to the construction of a device for holding and turning meat while being broiled over a fire in a cook-stove or range, without permitting the escape of smoke or odors into the apartment.

It consists in the peculiar construction and arrangement within a suitable case of a meat-holder and revolving cover, the case being placed on the top plate over an opening therein, and the meat-holder and cover operated in the manner more fully hereinafter set forth.

In the drawings—

A represents a cylindrical case, whose diameter is a trifle greater than that of the larger openings in the top plates of cook-stoves and ranges.

Within and near the bottom of the case is an inverted conical flange, a, which projects into the opening of the top plate over the fire.

B is a concaved or dished cover, easily fitting the interior of the case, and hung therein by its trunnions b b'. To the latter trunnion an opening, c, leads from the top of the case, the trunnion having a square channel cut longitudinally through it, while the trunnion b is a hollow cylinder closed at its outer end.

C is a meat-holder, formed of two circular grid-irons, preferably of iron wire, hinged to each other at d, where one of the sections is provided with a stud, e, which enters the socket in the trunnion b.

On the opposite side of the sections are secured the handles f, which have a square neck fitting the open channel c in the trunnion b.

To cook a juicy, toothsome steak with this broiler, set it over a hole in the stove over a clean fire, with the convex side of the cover down, place the steak between the sections of the meat-holder, close them together, and insert the stud e and necks of the handles in the trunnions, when, by turning the handles half around, the steak is then over the fire, covered closely by the cover B. When it is desired to examine the progress of the broiling, the parts are reversed, and, if the steak be found sufficiently cooked on one side, the holder is removed, reversed, and replaced, and proceed as before. The cover, fitting snugly to the walls of the case, prevents the escape of smoke or odor into the apartment.

A latch, ratchet, or other suitable device may be attached to either trunnion, to prevent accidental turning of the holder and cover, should the meat be not balanced equally on the axis of the holder.

What we claim as our invention, and desire to secure by Letters Patent, is—

1. The cover B, provided with trunnions b b', and revolving within the case A, as and for the purpose set forth.

2. The meat-holder C, made in two parts hinged together, and provided with stud e and handles f, said holder revolving with the cover B in the case A, in the manner described, and for the purpose specified.

DANIEL W. DENMAN.
WILLIAM K. TILLOTSON.
